By Scott H. Norvil
Attorney.

UNITED STATES PATENT OFFICE

2,453,361

ELECTRIC LINE DEICER

Clyde H. Clement, Phoenix, Ariz.

Application March 27, 1946, Serial No. 657,392

3 Claims. (Cl. 174—40)

1

This invention pertains to deicers for electrical transmission lines.

One of the objects of the invention is to provide a gravity actuated device which may be installed on transmission line poles between the insulator and the line and which will strike and vibrate the line wire whenever it becomes loaded with ice beyond a predetermined weight.

A further object is to provide a mechanism which may easily be attached to a line insulator, particularly the pendulum type, and will support the line so that when it becomes loaded with ice beyond a predetermined limit a counter balance will release a hammer which will strike the wire support so as to set up vibrations in the line and shatter the loading ice, whereafter, the line being lightened, the counter balance and hammer will be reset to non operative position until the line again becomes loaded with ice.

Other objects will appear hereinafter.

I attain the foregoing objects by means of the device illustrated in the accompanying drawings in which:

Figure 1 is a plan view of my de-icing device attached to a pendulum type insulator.

Figure 2, an elevational view thereof in a plane transverse to the line.

Similar numerals refer to similar parts of both views.

To the bottom lug 2 of insulator 3 a depending frame 4 is attached by pin 5. The frame includes a vertical member 6 on which the beam 7 is pivoted by bearing pin 8. This beam is composed of two bars 10 and 11 which straddle the lower end of member 6.

On the outer long end of this beam there is a line counter balancing weight 12 suspended on a metal strap 14 and pinned to the beam by bearing pin 15. The inner or shorter end of the beam carries a link 16, held by bearing pin 17 at its top. A standard line wire U bolt clamp 18 is pinned to the bottom end of this link. Extending inwardly beyond the inner end of beam 7 is a U-shaped hammer trip 20. The ends of this trip are welded to the ends of the beam bars 10 and 11, the curved portion joining these ends acts as a loop trip to engage trip prong 21 of hammer 22.

A transversely and outwardly extending hook shaped frame member 23 is welded to the upper part of frame member 6. Its outer end 24 is curved downward and somewhat back toward the shank of member 6, and is provided with a downwardly and inwardly extending pin slot 25.

The hammer 22 is a wedge shaped piece of metal plate drilled to receive bearing pin 26 at its

2

upper end and provided with a trip prong 21, extending radially from the pin axis.

It is to be noted that the main portion of weight 12 is cylindrical, but that a pin-bolt 27 extends thru it axially, and is adapted to carry a number of additional weight disks 28, shown in dotted outline Figure 1. Further adjustment of this weight is afforded by a plurality of pin receiving holes 29 positioned at intervals along the outer 10 end of beam 7.

In use the device is installed below a line insulator, as shown, and counter weight 12 set to support the load of the line wire 30 in the position shown in solid lines, Figure 2. Hammer 22 then 15 assumes the depending position similarly shown in solid lines in this figure. As the load on the line wire 30 increases due to a load of ice forming on each adjacent line span link 16 is depressed further and further and approaches the 20 position indicated by dotted outline 33 as weight 12 is raised toward the position indicated by dotted line 36 trip loop 20 traveling in an arcuate path 31 engages hammer prong 21 at position A, and rides on it until the prong traveling in an 25 arcuate path 34 passes out of the path of the trip at position B. The prong is then tripped and released and the outer portion swings from the position shown by dotted outline 37 to the lowered 30 position shown in solid lines where it strikes the line clamp 18. This causes the wire 30 to vibrate and surge from span to span sufficient to dislodge the weighting ice. When this drops the line is lightened and counter weight 12 raises the line to normal position again, as shown by the solid 35 lines. As the trip loop 20 swings upward it again encounters hammer prong 21, but is not impeded since the hammer and its prong are lifted upwardly and outwardly by reason of the pin 26 sliding in this direction in slot 25. In this way the 40 device automatically resets itself for another operation. Stop plates 38 on each side of frame member 6 limit the motion of beam 7 as desired.

As an example, the insulator load for a span of No. 0 copper wire is approximately 100 pounds. The counter weight can be 25 pounds, and the hammer 14 pounds. The whole device need not exceed 40 pounds and the saving in stresses from excess ice loads is remarkable.

While I have shown the device suspended from a pendulum type insulator, it is obvious that it may be attached to various sizes and types of line, telephone and other insulators, for example, a C-shaped bracket could be used to support the device above a pole top insulator. The operation 55 would be the same.

In view of its various uses and adaptability I wish to be limited only by the following claims.

I claim:

1. A deicer for electrical lines comprising a frame adapted to attachment to a pole insulator having a vertical member and an outwardly extending member, a beam pivotally mounted on said vertical member, having a counter weight on its outer end and a depending link on its inner end, a line wire clamp attached to the lower end of said link, and a hammer pivotally mounted on said outwardly extending frame member in an outwardly and upwardly extending slot therein, a trip prong extending radially from the axis of said hammer support, a trip loop carried on the inner end of said beam adapted to engage said hammer prong during a portion of its downward arcuate travel whereby said hammer is raised and released at the limit of said travel so that said hammer will fall and strike said line wire clamp; said hammer being supported so as to move out of the way of said trip during its upward arcuate swing.

2. A deicer for electrical lines comprising, a frame adapted for attachment to a pole insulator, a line balancing beam pivotally operative thereon, a line counterweight positioned on one end of said beam and a trip loop and line wire supporting link pivotally attached to the other end, a hammer pivotally mounted on said frame to swing from a horizontally extended raised position to a depending position contacting a line wire carried on said link, a trip prong on said hammer positioned to engage said trip loop thruout a portion of its downward arcuate travel thereby raising

said hammer to extended position, and to disengage said loop at a predetermined position along said arcuate travel whereby said hammer is released to descend and strike the line wire on said link, and means for raising said prong out of the way of said loop to allow free upward arcuate travel thereof.

3. A deicer for electrical lines comprising, a frame for support on a pole insulator, a line counter-balancing beam, operative thereon, adapted to carry the line wire in normal raised position when free of ice and in lowered position when loaded with ice, a hammer mounted on said frame adapted to swing from raised extended position to a lowered position in striking contact with said line wire, and mechanism including co-acting elements on said hammer and beam to raise said hammer as said beam is lowered by ice load on said line, an escapement to release said hammer from a predetermined raised position so that it falls to line wire striking position and reset mechanism arranged to permit said beam to return to normal position with said hammer in lowered position when said line wire is free of ice.
